[57] ABSTRACT

Cosmetics having a quality similar to that of the conventional cosmetics containing squalane, are prepared using at least one saturated, branched synthetic higher hydrocarbon having 26 to 48 carbon atoms, of the formula:

wherein R₁, R₂, R₃ and R₄ represent an alkyl group of 2 to 15 carbon atoms, and R₁ is different from R₂ and R₃ is different from R₄, and other cosmetic additives.

4 Claims, No Drawings

**COSMETICS CONTAINING SATURATED,
BRANCHED SYNTHETIC HIGHER
HYDROCARBON**

The present invention relates to cosmetics, more particularly, relates to cosmetics containing as a cosmetic base, a synthetic higher hydrocarbon having excellent physiological properties.

Broadly speaking, the conventional cosmetic contain a cosmetic base consisting of saturated higher hydrocarbons selected from higher mineral hydrocarbons, for example, liquid paraffins, higher animal hydrocarbons, for example, squalane which is prepared by completely hydrogenating squalene obtained from fish liver oil, and higher vegetable hydrocarbons, for instance, completely hydrogenated terpenes and polymerized terpenes.

The liquid mineral paraffins consist of a mixture of multiple component hydrocarbons, varying in molecular weight and chemical structure. Sometimes, some of the component hydrocarbons stimulate human skin and are easily decomposed by the action of micro-organisms. Accordingly, the liquid paraffins guarantee little in cosmetic quality, that is, they neither ensure non-irritation to human skin nor stability during prolonged storage.

The vegetable hydrocarbons also include a plurality of component hydrocarbons varying in number of carbon atoms and chemical structure. Therefore, the vegetable hydrocarbons sometimes include undesirable component hydrocarbons having considerable stimulating effect on human skin and low resistance to micro-organisms.

It is known that squalane is a simple higher animal hydrocarbon of 30 carbon atoms and does not stimulate human skin and has an excellent stability in storage. However, since the squalane is prepared from squalene include in fish liver oil which is not always readily available, the supply of squalane is limited and variable in quantity.

Due to the above-stated circumstances, it is strongly desired by the cosmetic industry that uniform quality higher hydrocarbons usable as the cosmetic base, producing non-irritation of human skin and having high stability in relation to biological activity can always be obtained in a desired quantity without difficulty. For

this purpose, it is desirable to obtain simple synthetic higher hydrocarbons having similar cosmetic properties to those of squalane.

One object of the present invention is to provide cosmetics comprising, as a cosmetic base, a synthetic higher hydrocarbon having a non-stimulative property, a high stability to the action of micro-organisms, and other physiological properties.

The other object of the present invention is to provide cosmetics, for example, skin, hair, make-up, bath and toilet cosmetics, comprising a cosmetic base effective for protecting the human body from the action of micro-organisms, with sufficient safety.

The above-stated objects are accomplished by the cosmetics of the present invention. The cosmetics of the present invention comprise a base consisting of at least one saturated, branched synthetic higher hydrocarbon having 26 to 48 carbon atoms, of the formula:

wherein R_1 , R_2 , R_3 and R_4 represent an alkyl radical of 2 to 15 carbon atoms, but R_1 differs from R_2 and R_3 differs from R_4 , and other cosmetic additives.

The synthetic higher hydrocarbons usable for the present invention are ideal for the cosmetic base.

That is, the synthetic higher hydrocarbons of the present invention can eliminate the above-mentioned drawbacks of the conventional cosmetic base, and be stored for a prolonged period without deterioration. Also, the synthetic higher hydrocarbons of the present invention are greatly effective for protecting human skin from chemical and physical stimulation, preventing the penetration of micro-organisms into the human body, and maintaining human skin in a normal physiological condition even if circumstance changes.

Table 1 indicates physical properties of the typical synthetic higher hydrocarbons usable for the present invention. Further, Table 1 shows the physical properties of the synthetic hydrocarbons of less than 26 carbon atoms and squalane, namely, 2,6,10,15,19,23-hexamethyl-tetracosane.

Table 1

The synthetic higher hydrocarbons usable for the present invention are prepared, for example, by the procedures detailed below.

Preparation of the Synthetic Higher Hydrocarbon Usable for the Present Invention

The synthetic higher hydrocarbons usable for the present invention include 26 to 48 carbon atoms. The hydrocarbons of less than 26 carbon atoms are not to be considered for the cosmetic base because of too low viscosity and excessive stimulation to human skin. Also, the hydrocarbons having more than 48 carbon atoms are unsuitable for use as cosmetic base because of excessive viscosity and poor spreadability.

The synthetic higher hydrocarbons usable for the present invention may be prepared by the conventional methods for synthesizing alkane compounds. For example, the synthetic higher hydrocarbons may be prepared in accordance with the Wurtz reaction or Frankland reaction. That is, two saturated branched hydrocarbon halides of the formula:

wherein R₁ through R₄ are the same as defined above and X-trimethyl-halogen atom selected from the group consisting of chlorine, bromine and iodine, in the presence of a dehalogenating agent, for example, metallic sodium, potassium, magnesium, silver, copper or zinc.

1. Preparation of

2,2,4-trimethyl-10-ethyl-7-(1,3,3-trimethylbutyl)tetradecane and

2,2,4,13,15,15-hexamethyl-7,10-bis(1,3,3-trimethylbutyl)hexadecane

The above-mentioned hydrocarbon compounds were prepared by condensing 2-ethylhexyl bromide and 5,7,7-trimethyl-2(1,3,3-trimethylbutyl)octyl bromide.

The 2-ethylhexene-2-a-1 was prepared by condensing n-butylaldehyde in an aqueous solution of 2% by weight of sodium hydroxide, and then, converted to 2-ethylhexanol by hydrogenating in the presence of a raney nickel catalyst. A mixture of one mol of 2-ethylhexanol and 2.1 mols of hydrobromic acid (which was an aqueous solution of more than 47% of hydrobromic acid, having a specific gravity of 1.48) was charged into a one litre, three neck flask, and then, 1 part by mol of concentrated sulfuric acid was added by drops while the flask contents were being cooled with ice. Thereafter, the reaction mixture was gradually heated while

stirring to a temperature of 130° - 140°C and maintained at that temperature for 6 hours. The reaction product was diluted with hexane, successively washed with water, concentrated sulfuric acid, water and thereafter, an aqueous solution of sodium carbonate, dried over calcium chloride and then, distilled.

2-ethylhexyl bromide having a boiling point of 84 to 86°C, under a pressure of 15 mmHg, was obtained in an amount of 167 g (yield: 86.5%).

The 5,7,7-trimethyl-2(1,3,3-trimethylbutyl)octyl bromide was prepared by the following procedure.

3,5,5-trimethyl-hexyl aldehyde was prepared from isooctene by oxo synthesis (hydroformylation) and then, converted to 5,7,7-trimethyl-2(1,3,3-trimethylbutyl) octanol by the aldol condensation process. The 5,7,7-trimethyl-2(1,3,3-trimethylbutyl) octanol was converted to 5,7,7-trimethyl-2(1,3,3-trimethylbutyl)octyl bromide having a boiling point of 120° - 128°/2 mmHg by reacting with the hydrobromic acid in the same procedure as that of the 2-ethylhexyl bromide, in an yield of 72.7%. The condensation of the 2-ethylhexyl bromide with the 5,7,7-trimethyl-2(1,3,3-trimethylbutyl)octyl bromide was effected by the following procedure.

40 A 100 ml three neck flask was charged with a reaction mixture of 0.085 mol of the 2-ethylhexyl bromide and 0.085 mol of the 5,7,7-trimethyl-2(1,3,3-trimethylbutyl)octyl bromide. 0.187 mol of metallic sodium was added to the reaction mixture, which was being cooled with ice and stirred for 5 hours under the cooled condition. The non-reacted metallic sodium was treated with methanol and water. The reaction product was dried with anhydrous sodium sulfate and then distilled to isolate the resultant hydrocarbon compounds from each other. By the distillation, (A) 5,8-diethyl-dodecane

50 having 14 carbon atoms, a boiling point of 150° - 155°C/32 mmHg, a viscosity at 25°C of 45 cps, a specific gravity at 19°C of 0.7798 and a freezing point of lower than -80°C was obtained in a yield of 9.8%, (B)

55 2,2,4-trimethyl-10-ethyl-7(1,3,3-trimethylbutyl)tetradecane having 26 carbon atoms, a boiling point of 160° - 180°C/1 mmHg, a viscosity at 25°C of 35.0 cps, a specific gravity at 19°C of 0.7980 and a freezing point of lower than -80°C was obtained in a yield of 78.4% and

60 (C) 2,2,4,13,15,15-hexamethyl-7,10-bis(1,3,3-trimethylbutyl)hexadecane having 36 carbon atoms, a boiling point of 180° - 200°C/10⁻² mmHg, a viscosity at 25°C of 636 cps, a specific gravity at 19°C of 0.8159 and a freezing point of lower than -80°C was obtained in a yield of 10.0%.

The hydrocarbon compounds (B) and (C) thus obtained are novel compounds of the present invention and have the formulae (I) and (II).

2. Preparation of 9,12-dihexyl eicosane

The 9,10-dihexyl eicosane was prepared by condensing 2-hexyldecanol chloride which was obtained in the following procedure.

2-hexyl decanol was prepared from n-octylaldehyde in the same procedure as that of the 2-ethyl hexanol in Example 1. A reaction mixture of 2 mols of the 2-hexyldecanol and 3 mols of pyridine was charged into a 2 litre three neck flask and 2.4 mols of thionyl chloride were added by drops while the mixture was stirred and cooled with ice. After completing the addition of the thionyl chloride, the reaction mixture was heated at a temperature of 120° to 140°C for 8 hours. The reaction product was diluted with hexane, successively washed with concentrated sulfuric acid, water and an aqueous solution of sodium carbonate, dried with anhydrous sodium sulfate and then distilled. By the distillation, 2-hexyldecanol chloride, with a boiling point of 120° - 125°C/3 mmHg was obtained in an amount of 276 g (yield: 53%).

The 2-hexyldecanol chloride thus obtained was converted to 9,12-dihexyl-eicosane by the following procedure.

The 2-hexyldecanol chloride in an amount of 0.274 mol was charged into a 200 ml three neck reaction flask, 0.275 mol of metallic sodium was added, while stirring, at room temperature and then maintained at a temperature of 120° to 140°C while stirring for 2 hours. Thereafter, the reaction mixture was heated at a temperature of 130°C for 8 hours. The non-reacted metallic sodium was deactivated with ethanol. The reaction product was diluted with hexane, washed with water, dried with anhydrous sodium sulfate and then, distilled. By the

distillation, boiling -dihexyl eicosane having 32 carbon atoms, a boiling point of 180° - 210°C/1 - 2 mmHg, a viscosity at 25°C of 31.5 cps, a specific gravity at 19°C of 0.8230 and a freezing point of lower than -8.0°C was obtained in a yield of 35%. The 9,12-dihexyl eicosane is a novel compound of the present invention and has the following formula

3. Another Preparation of 9,12-Dihexyl Eicosane

The 9,12-dihexyl eicosane was prepared by condensing 2-hexyldecanol bromide.

The 2-hexyldecanol bromide was prepared from 2-hexyl decanol using the same method as that of 2-ethylhexyl bromide in Example 1.

A 500 ml three neck reaction flask was charged with 0.1 mol of metallic magnesium and a small amount of iodine, and a small amount of the 2-hexyldecanol bromide was added by drops. Thereafter, a solution of 0.2 mol of the 2-hexyldecanol bromide in 200 ml of anhydrous ether was further added by drops into the reaction flask. The reaction mixture was heated at a temperature of 55° - 65°C for 24 hours while refluxing, and

then, the ether was distilled away from the reaction mixture. Next, the reaction mixture was maintained at a temperature of 120°C for 48 hours. The reaction product was treated with hydrochloric acid, extracted by hexane, dried with anhydrous sodium sulfate and then, distilled. As a result of the distillation, 9,12-dihexyleicosane having the same physical properties as those in Example 2 was obtained in a yield of 20%.

4. Preparation of 11,14-Dioctyl Tetracosane

The above-captioned hydrocarbon compound was prepared by condensing 2-octyl dodecyl bromide which was prepared by the following procedure.

A mixture of 2-octyl dodecanol and the sodium salt of n-nonanoic acid was prepared by heating n-decanol at a temperature of 200° to 230°C in the presence of sodium hydroxide. From the mixture, 2-octyl dodecanol was isolated by extraction and distillation. The 2-octyl dodecanol thus obtained, was converted to 2-octyldodecyl bromide having a boiling point of 175° - 185°C/3 mmHg by treating with hydrobromic acid in the same as that for 2-ethyl hexanol in Example 1.

The condensation of the 2-octyldodecyl bromide was carried out by heating together with metallic sodium at room temperature for 16 hours, at 55°C for 6 hours and then, at 150°C for 4 hours. The condensation product was treated in the same method as that for the condensation product in Example 1. As a result of the treatment, 11,14-dioctyl tetracosane having 40 carbon atoms, a boiling point of 200° - 220°C/10⁻² mmHg, a viscosity at 25°C, of 52.5 cps, a specific gravity at 19°C of 0.8169 and a freezing point of 7.5° - 10.5°C was obtained in a yield of 74%.

The hydrocarbon compound thus prepared has the following formula IV:

Testing of the Synthetic Higher Hydrocarbons Usable for the Present Invention

1. Stimulation of Animal Skin by One Application

For each of the six kinds of synthetic higher hydrocarbons as shown in Table 2, eight albino rabbits were used. They were divided into two groups of four and their hair was cut at the portion to be tested. The rabbits in one of the groups had their skin scraped from the test portions. However, the skin of remaining rabbits was kept intact. All the rabbits were secured by immobilizing equipment. The six kinds of synthetic higher hydrocarbons shown in Table 2 were applied, in an amount of 0.5 ml. onto a 2.5 cm square piece of lint fabric. The lint pieces bearing the synthetic higher hydrocarbons were put on the test portions of the rabbits so as to bring the applied synthetic higher hydrocarbon layer into contact with the skin. The lint pieces were covered by 3.5 cm square gauzes secured onto the test

portions by adhesive tapes and further completely covered by rubber dams. The rabbits were maintained for 72 hours under the above-mentioned test conditions. After 24 hours the lint pieces on the rabbits were removed and the test portions were observed for red spots (erythema) and dropsical swellings (edema). The erythema and edema thus observed were valued in accordance with the predetermined evaluation standards as detailed hereinafter. Thereafter, the lint pieces were re-applied for the remaining 48 hours. After the testing was completed, the same evaluation as stated above was repeated.

Evaluation Score for Erythema

	Score
Erythema	
No erythema	0
Slight erythema	1
Clear erythema	2
Extreme erythema	3
Extreme erythema and slight desquamation	4

Evaluation Score for Edema

	Score
Edema	
No edema	0
Very small edema	1
Small Edema	2
Edema of about 1 mm diameter	3
Extreme edema larger than lint piece	4

The respective results of evaluations for the erythema and edema were combined and averaged, and those averaged values for the erythema and edema were again averaged. The averaged values were estimated as follows.

35

Averaged value	Estimation of the averaged values	
	Estimation	
Less than 2.0	:	substantially no stimulation or very little irritation to animal skin
2.1 to 3.0	:	normal irritation
More than 3.1	:	very strong irritation

45

The results are shown in Table 2.

2. Irritation of Animal Skin by Three Applications

For each of the synthetic higher hydrocarbons, three 50 guinea-pigs were used. Their hair was cut at the portion to be tested. The synthetic higher hydrocarbon was applied in an amount of 0.3 ml onto the test portion. After testing for 24 hours, the same application of the synthetic higher hydrocarbon as stated above was repeated 55 twice onto the test portion.

After the test was completed the test portions of the 60 guinea-pigs were observed for erythema and edema formations. The observed erythema and edema were valued in accordance with the same evaluation standards as those stated hereinbefore. The results are shown in Table 2.

For comparison, the same test as those stated above were repeated using the liquid paraffin, squalane, 5,8-diethyl dodecane and 5-ethyl-8-hexyl hexadecane. The 65 results are shown in Table 2.

Table 2-Continued

Hydrocarbon	umber of carbon atom	Stimulation of albino rabbit skin by one application	Stimulation of guinea-pig skin by three applications
The present invention	2,2,4-trimethyl-10-ethyl-7-(1,3,3-trimethylbutyl)tetradecane	26	0.19
	5-ethyl-8-octyl octadecane	28	0
	2,2,4-tri-methyl-7-(1,3,3-tri-methyl-butyl)eicosane	30	0
	9,12-dihexyl eicosane	32	0
	2,2,4,13,15,15-hexamethyl-7,10-bis(1,3,3-tri-methylbutyl)hexadecane	36	0
	11,14-dioctyl-tetracosane	40	0
	Average		0.19
	Liquid paraffin	20	0.69
	5,8-diethyl dodecane	16	2.3
	5-ethyl-8-hexyl hexadecane	24	0.69
Other than the present invention	Squalane	30	0
			0.33

Table 2 clearly shows that the synthetic higher hydrocarbons of the present invention had practically no stimulation of animal skin. This is the same as that of squalane. However, the fluid paraffine and the comparative hydrocarbons having less than 26 carbon atoms had high stimulation of animal skins.

Since it was observed that the synthetic higher hydrocarbons of the present invention are harmless to animal skin, the harmlessness to human skin of the synthetic higher hydrocarbons usable for the present invention, was confirmed by the testing detailed below.

3. Irritation of Human Skin

One hundred girls were subjected for testing the synthetic higher hydrocarbons of the present invention as shown in Table 2 and squalane. The higher hydrocarbons were applied in an amount of 0.05 ml onto lint pieces. The lint pieces were put on the subjects' forearms or the inner aspects of their elbows covered by special adhesive tapes and secured by bandages. The test were continued for 48 hours. Observations were made after 24 hours and 48 hours, for erythema, edema, papules and blisters. With respect to all the tested hydrocarbons, no change was observed on any of the test portions of the subjects. The synthetic higher hydrocarbons of the present invention as shown in Table 2 were further subjected to tests which might indicate stimulation of the mucous membranes of the eyes involving the cornea, iris and conjunctive which were observed at predetermined intervals of time. Also tests were carried out to observe effect on human skin and effects of acute toxicity resulting from ingestion of

doses of 25 ml/kg body weight. All the results of the tests were negative. That is, the excellent safety of the synthetic higher hydrocarbons of the present invention was confirmed.

4. Stability Against Bacterial Decomposition

Five hydrocarbon compounds as shown in Table 3 were subjected to a test for stability against bacterial decomposition.

10 Two kinds of bacteria, *Pseudomonas aeruginosa* and *Pseudomonas* Strain No. 23 (non-identified) were cultured in the culture media under the conditions detailed below.

1. Composition of culture medium

10 g hydrocarbon compound to be tested
2.5 g K_2HPO_4
0.5 g KH_2PO_4
0.3 g $MgSO_4$
0.3 g $CaCl_2$
3.0 g $(NH_4)_2SO_4$
0.3 g $NaCl$
1000 ml water

2. Culture condition

25 30 ml of culture medium was charged into a 100 ml shaking flask sterilized in an autoclave at a high temperature, and allowed to cool to room temperature. One platinum loop of the bacterial suspension was inoculated into the culture medium. The inoculated culture medium was shaken at a frequency of 120/minutes at a temperature of 30°C for 7 days to culture the bacterium.

The multiplication of the bacterial fungus bodies was determined by the method detailed below.

35 2 ml of 0.006% dilution water and 2 to 4 drops of 1N-aqueous solution of H_2SO_4 was uniformly mixed with 2 ml of the culture liquid. The mixture was subjected to centrifugal isolation. The resulting precipitation was washed with petroleum ether, and further subjected to the centrifugal isolation. The isolated precipitate was suspended in water. The suspension was subjected to the measurement of absorption at 660 m μ using a spectrophotometer to determine the degree of multiplication in the bacterial fungus bodies. The higher the absorption, the larger the multiplication.

The degree of multiplication was expressed in terms of the references detailed below.

50	++	Great multiplication
	+	Normal multiplication
	$\pm$	Impossible to determine
	-	No multiplication

55 For example, six kinds of hydrocarbon compounds were used instead of the hydrocarbons of the present invention and the multiplication was measured.

The results are shown in Table 3.

					35

From Table 3, it was established that the higher saturated branched hydrocarbon compounds of the present invention have a higher stability against bacterial decomposition than that of the conventional fluid paraffins, even when the synthetic higher hydrocarbons of cosmetics containing the hydrocarbons are applied onto or sprinkled over human skin in atmosphere. This indicates that the synthetic higher hydrocarbons of the present invention have a high ability to keep the perfume of the cosmetics for a prolonged time and thus, are highly valuable as the cosmetic base.

The synthetic higher hydrocarbons of the present invention can be utilized as a cosmetic base for the treatment and make-up products, such as O/W type nutritious cream, W/O type nutritious cream, pomade, lipstick, bath oil, skin lotion, skin moisturizer, eye make-up and body lotion. The cosmetics are prepared by making the synthetic higher hydrocarbon with the other cosmetic ingredients, for example, cetylalcohol, vaseline, lanoline, polyoxyethylene cetylalcohol ether, polyethylene glycol, bees wax, sorbitan monooleate, polyoxyethylene sorbitan monooleate, glycerol trioleate, ceresine, microcrystalline wax, lanoline wax, olive oil, polyoxyethylene oleyl alcohol ether, perfumes, coloring matters, antioxidanting agents, antiseptics, and ultra-violet ray absorbers.

Various methods of practicing the present invention are illustrated by the following examples. These examples are intended merely to illustrate the present invention and not in any sense to limit the manner in which the present invention is practised. The percentages recited therein are based on weight.

EXAMPLE 1

An O/W type nutritious cream was prepared by the procedure as detailed below.

A mixture of 14% of 5-ethyl-8-octyl octadecane, 3% of cetylalcohol, 3% of vaseline, hereinafter also referred to as "petrolatum", and 2% of hydrous lanolin was melted at a temperature of 50° to 60°C while stirring. The melt was emulsified in 7% of ion-exchanged water containing 3% of polyoxyethylene cetylalcohol ether and 2% of polyethylene glycol, and then small amounts of perfume and antiseptic were added into the emulsion.

For comparison, the same procedures as stated above were repeated using squalane instead of 5-ethyl-8-octyl octadecane.

The nutritious cream of the present example had cosmetic qualities similar to those of the comparison cream.

EXAMPLE 2

A W/O type nutritious cream was prepared by the following procedures.

40% 9,12-dihexyl eicosane was mixed with 10% of bees wax and 10% of hydrous lanoline. The mixture was heated at a temperature of 50° to 60°C while stirring to form a uniform solution 36% of ion-exchanged water containing 3% of sorbitan monooleate and 1% of polyoxyethylene sorbitan monooleate were emulsified into the solution. A small amount of perfume and anti-septic were added to the emulsion.

The resulting W/O type nutritious cream had excellent cosmetic properties.

EXAMPLE 3

A lipstick was prepared by the following procedures. A mixture of 20% of 11,14-diethyltetracosane, 35% of glycerol trioleate, 20% of ceresine (solid paraffin), 5% of microcrystalline wax and 10% of lanolin wax was melted at 95° to 100°C while stirring. The melt was mixed with 10% of a mixture containing 50 parts by weight of a lake pigment and 50 parts of triglyceride of oleic acid and a necessary amount of dye solution and a perfume. The mixture was molded in a lipstick mold.

The lipstick thus formed was found to be satisfactory in cosmetic quality.

EXAMPLE 4

A pomade was prepared by the following method. 9% of 9,12-dihexyl eicosane was mixed with 52% of white vaseline, 6% of solid paraffin and 30% of olive oil and the mixture was melted at a temperature of 80°C while stirring. The melt was mixed with a necessary amount of coloring matter. The colored melt was allowed to cool to a temperature of 40° - 50°C and mixed with 3% of a perfume and a necessary amount of an antioxidanting agent while stirring. The mixture was fed into a container and allowed to cool to room temperature.

The resulting pomade was found to be satisfactory in cosmetic quality.

EXAMPLE 5

A bath oil was prepared by the procedures detailed below.

50% of 2,2,4-trimethyl-10-ethyl-7(1,3,3-trimethylbutyl) tetradecane and 25% of 2,2,4,13,15,15-hexamethyl-7,10-bis(1,3,3-trimethylbutyl)hexadecane were uniformly mixed with 15% of glycerol trioleate, 5% of polyoxyethylene oleyl alcohol ether and 5% of a perfume. The mixture was heated at 40° to 50°C while stirring.

The resultant bath oil was found to be satisfactory in cosmetic quality.

What we claim is:

1. In a method of cosmetically treating human skin comprising application of a non-irritating cosmetic composition comprising conventional cosmetic agents, the improvement which comprises employing as a non-irritating cosmetic base of said cosmetic composition at least one saturated, branched synthetic higher hydrocarbon having 26-48 carbon atoms and having the structural formula:

13

wherein R₁, R₂, R₃ and R₄ represent an alkyl radical of 2 to 15 carbon atoms respectively, but R₁ differs from R₂ and R₃ differs from R₄.

2. The method of claim 1, wherein said saturated, branched higher hydrocarbon is selected from the group consisting of 2,2,4-trimethyl-10-ethyl-7-(1,3,3-trimethylbutyl)tetradecane, 5-ethyl-8-octyl-octadecane, 2,2,4-trimethyl-7-(1,3,3-trimethylbutyl)eicosane, 9,12-dihexyl-eicosane, hexaethyl-eicosane, 5-ethyl-8-decyl-eicosane, 2,2,4,13,15,15-hexamethyl-7,10-bis(1,3,3-trimethylbutyl)hexadecane, 9-hexyl-12-octyl-docosane, 2,2,4-trimethyl-7-(1,3,3-trimethylbutyl)-10-octyl-eicosane, 11,14-dioctyl-tetracosane, 9-hexyl-12-decyl-tetracosane, 2,2,4-trimethyl-7-(1,3,3-trimethylbutyl)-10-decyl-docosane, 11-octyl-14-decyl-hexacosane and 13,16-didecyl-octacosane.

3. In a cosmetic composition comprising conventional cosmetic agents, the improvement which comprises employing as a non-irritating cosmetic base of said cosmetic composition at least one saturated,

14

branched synthetic higher hydrocarbon having 26 to 48 carbon atoms and having the structural formula;

5

10

wherein R₁, R₂, R₃ and R₄ represent an alkyl radical of 2 to 15 carbon atoms, respectively, but R₁ differs from R₂ and R₃ differs from R₄.

4. The cosmetic composition of claim 3, wherein said saturated, branched higher hydrocarbon is selected from the group consisting of 2,2,4-trimethyl-10-ethyl-7-(1,3,3-trimethylbutyl)tetradecane, 5-ethyl-8-octyl-octadecane, 2,2,4-trimethyl-7-(1,3,3-trimethylbutyl)eicosane, 9,12-dihexyl-eicosane, hexaethyl-eicosane, 5-ethyl-8-decyleicosane, 2,2,4,13,15,15-hexamethyl-7,10-bis(1,3,3-trimethylbutyl)hexadecane, 9-hexyl-12-octyl-docosane, 2,2,4-trimethyl-7-(1,3,3-trimethylbutyl)-10-octyl-eicosane, 11,14-dioctyl-tetracosane, 9-hexyl-12-decyl-tetracosane, 2,2,4-trimethyl-7-(1,3,3-trimethylbutyl)-10-decyl-docosane, 11-octyl-14-decyl-hexacosane and 13,16-didecyl-octacosane.
